UNITED STATES PATENT OFFICE.

CRAWFORD THEODORE WESTMORELAND, OF HIGH POINT, NORTH CAROLINA, ASSIGNOR
TO MYRTLE DESK COMPANY, A CORPORATION OF NORTH CAROLINA.

LOCKING DEVICE FOR DESKS AND THE LIKE.

1,139,940.

Specification of Letters Patent. Patented May 18, 1915.

Application filed January 3, 1913. Serial No. 740,082.

To all whom it may concern:

Be it known that I, CRAWFORD THEODORE WESTMORELAND, a citizen of the United States, residing at High Point, in the county of Guilford and State of North Carolina, have invented certain new and useful Improvements in Locking Devices for Desks and the like, of which the following is a specification.

- 10 This invention relates to improvements in locking devices for desks, cabinets or other pieces of furniture having a plurality of drawers the locking of which is controlled by some movable portion usually under control of lock and key and common to all the drawers. For example, in the case of roll top desks it is common to control the locking of the tiers of drawers by the roll top, and in the case of a flat top desk to control the locking of a plurality of the drawers from one drawer, which latter is locked and unlocked by a key. It is a common fault with devices of this character now generally in use that the locking mechanism for the several 15 drawers easily gets out of order, due in some cases to the more or less complex mechanism employed, and in others to faulty construction which will not stand the rough usage to which such mechanism is ordinarily subjected. The ideal mechanism for this purpose should be, without sacrificing certainty of operation, simple in construction and of such a nature as to stand rough or severe operation without getting out of order.
- 20 25 30 35 The object of this invention is to provide a locking device of the above character which shall possess the desirable qualities stated.

In order to more fully describe my said invention, reference will be had to the accompanying drawings wherein—

Figure 1 represents a vertical section of a desk of the flat top type equipped with a form of my invention particularly adapted to desks of that type; Fig. 2, a fragmentary top plan view of the desk and locking mechanism shown in Fig. 1, with the flat top of the desk removed; Fig. 3, a fragmentary section on line 3^x—3^x Fig. 1, looking down, and Fig. 4, a detail fragmentary perspective view partly in section of the locking mechanism shown in Fig. 1.

Referring to the accompanying drawings, 1 represents a desk of the flat top type having a tier of drawers 2, 3 and 4.

My improved locking device, in the form shown in this case, comprises a fixed upright 5 made fast top and bottom, respectively, to two brackets 5^a and 5^b secured to the back of the desk, locking dogs 6 and 7 fulcrumed on 60 said upright; a movable member 8 to which the tails of all the locking dogs are pivotally secured; a separable extension 9 on the upper end of said member 8; a spring 10 connecting the member 8 and its extensions 9, 65 and a lever 11 fulcrumed on the stationary member 5, and pivotally connected to the separable extension 9. The heads of the several dogs are provided, respectively, with shoulders 12 and 13, adapted to engage the 70 inner side of the rear ends of the drawers 3 and 4, and with rounded cam edges 14 and 15, the purpose of which will hereinafter more readily appear. The extension 9 is held in proper alinement by means of a pin 75 16 on the upper end of the member 8 which extends into a recess 17 in the extension member, as shown most clearly in Fig. 3. The spring 10 is made fast at one end to the member 8 and at its other end to the member 9, and normally holds said members together, as shown in Fig. 1. The lever 11 is adapted to be operated by the upper drawer 2 which drawer is the one usually locked by a lock and key, and which controls the locking of the other drawers, and for this purpose said lever is provided with a rounded face 18 for engagement with the rear end of said drawer.

The operation is as follows: With all the drawers closed, as shown in Fig. 1, the rear end of drawer 2 abuts against the lever 11 and causes the same to hold the member 8 in the up position, whereby the dogs are held in the locked position shown. When the pressure of the end of the drawer 2 is released from the lever 11, as when said drawer is pulled forward, the member 8 drops by gravity, and in doing so raises the locking heads of the dogs 6 and 7 clear of the tops of the rear end of the drawers 3 and 4, thereby unlocking said drawers and leaving them free to be pulled out. Should either or both of the drawers 3 and 4 be left in the unlocked position after the top drawer is closed, which position of the top drawer would send the dogs into the locking position, the drawers 3 and 4 will lock on closure. In such a case the rear ends of the drawers 3 and 4 would engage the cam faces 105 110

14 and 15 of the dogs and force them up to permit passage of the ends of the drawers into locking engagement with the dogs. In this case the heads of the dogs would 5 yield upwardly against the tension of the spring 10 which would extend to permit the member 8 to descend. After the drawers pass into the locking position, the spring 10 pulls the member 8 up and sends the heads 10 of the dogs down to engage and lock the drawers. The downward movement of member 8 and the upward movement of the heads of the locking dogs is limited by stops 19 and 20.

15 I preferably make the locking dogs of metal, though the lever 11 is preferably made of wood. I do not, however, limit the making of the parts of my invention to any special material.

20 The locking mechanism herein shown and described is, as will be readily seen, extremely simple, and is particularly free from liability to get out of order.

Another important advantage of my improved locking device is that the whole mechanism, including the attachment of the upright 5 to the brackets 5^a and 5^b, may be assembled before it is put in the desk.

The employment of a separable member 30 such as 8—9 extensible against a spring as shown, constitutes a very simple and efficient arrangement for permitting the dogs to yield as described. Also, the form of locking dog herein shown may be and preferably is stamped out of plate or sheet metal which greatly reduces the cost of manufacture. At the same time these dogs will not split or break in operation as is the case with the wooden locking members commonly in 40 use.

It should be understood, however, that while I have herein shown my invention as applied to desks only, it may equally as well be applied to cabinets, or other pieces of furniture having a series of drawers, the locking of which is controlled from some one movable part of the article ordinarily under lock and key, and in the claims I use the word desk in a generic sense to cover all 45 such articles. It will be further understood that modifications may be made in the construction of the locking mechanism itself without departing from the true spirit of my invention.

50 What I claim is:—

1. A desk having a plurality of drawers, in combination with a locking device therefor comprising a stationary support, a plurality of dogs fulcrumed thereon and adapted 55 to lock said drawers, a movable member to which the tails of all said dogs are pivotally connected, means operative by a movable portion of the desk and operatively

connected to said movable member, and a spring mounted wholly on said movable member and forming a portion of said operative connection to lift said movable member.

2. A desk having a plurality of drawers, in combination with a locking device therefor comprising a stationary support, a plurality of dogs fulcrumed thereon and adapted to lock said drawers, a movable member to which the tails of all said dogs are pivotally connected, a lever adapted to be operated by a movable portion of the desk, and a yielding connection between said lever and said movable member through which said movable member is lifted by said lever.

3. A desk having a plurality of drawers, in combination with a locking device therefor, comprising a stationary support, a plurality of dogs fulcrumed thereon and adapted to lock said drawers, a separable movable member at one section of which the tails of all said dogs are pivotally connected, a spring mounted wholly on said movable member and forming a connection between the separable sections of said member, and means connected to one of the sections of 90 said member and operative by a movable portion of the desk to lift the other section through said spring.

4. A desk having a plurality of drawers, in combination with a locking device therefor comprising a stationary support, a plurality of locking dogs fulcrumed on said support and adapted to engage the rear ends of said drawers, a movable member pivotally connected to the tails of the several dogs, a lever fulcrumed on said support, and operable by a movable portion of said desk to operate all of said dogs simultaneously, and a spring mounted wholly on said movable member and forming a portion of the connection between said lever and member, and against which any of said dogs in the locking position may yield to receive the rear end of the drawers to lock the same.

5. A locking device for desks or the like, comprising a rod or bar, a series of locking dogs fulcrumed on said bar, a bar made in two separable sections to one of which the tails of all said dogs are pivotally connected, a lever fulcrumed on the first named bar 115 and pivotally connected to the other sections of the separable bar, and a spring forming a yielding connection between the sections of said separable bar.

In testimony whereof I affix my signature 120 in presence of two witnesses.

CRAWFORD THEODORE WESTMORELAND.
